PITCHING SHOE

Filed April 26, 1939

UNITED STATES PATENT OFFICE

2,219,972

PITCHING SHOE

George A. Altendorf, Oshkosh, Wis., assignor to
 Giant Grip Manufacturing Company, Oshkosh,
 Wis., a corporation of Wisconsin

Application April 26, 1939, Serial No. 270,227

7 Claims. (Cl. 273—106)

This invention relates to pitching shoes or the like of the type employed in games or contests where the shoe is pitched through the air toward a distant pin or stake in an effort to embrace or encircle the pin with the shoe or otherwise get it as close as possible to the pin, and is more particularly concerned with pitching shoes which are especially adapted for indoor and like uses.

In its preferred embodiment, the invention comprises pitching shoes which comprise a weighted core member covered with a relatively soft or resilient material such as rubber. The shoes must be weighted to make them suitable for the purposes of the game and at the same time should be soft surfaced so as not to injure the floor, furniture or other surfaces adjacent the pin.

Open sided pitching shoes of steel or some similar material have long been used in outdoor games, being shaped somewhat similarly to the familiar open sided horse shoes which were originally used in the game, and which are still used in some outdoor games.

This game could not be played with metal indoors without danger of scarring or denting the floor or surrounding furniture, and it has been heretofore proposed to provide pitching shoes for indoor use wherein a continuous metal core was imbedded in rubber. These latter shoes, while softer than all metal shoes, are objectionable in that they become permanently deformed after constant use due to progressive bending of the core caused by repeated shocks. Hence there is no manner of insuring a uniform opening at the side of such a shoe during its use.

Another major objection to these rubber covered pitching shoes of the prior art has been that they are too live and springy and tend to rebound and bounce excessively when they land on hard surfaces such as flooring or the like.

With the above defects of the prior art in mind, it is a major object of the present invention to provide a novel pitching shoe which is surfaced with relatively soft or resilient material to adapt it for indoor and similar uses and which possesses sufficient weight and ability to substantially sustain a given shape to make it a substantial equivalent in those respects of hard metal outdoor pitching shoes and which is designed to eliminate excessive rebound and bounce when the shoe falls upon a relatively hard floor or similar surface.

A further object of the invention is to provide a novel open sided pitching shoe wherein a sectional core member of substantial weight is imbedded in a resilient surfacing material such as rubber. Specifically the shoes are usually of generally U

or horseshoe-shape, and the core member comprises two or more pivotally interconnected rigid metal arms permanently secured as by vulcanizing to the rubber surfacing material.

A further object of the invention is to provide a novel open sided pitching shoe whose legs are capable of limited relative movement only when subjected to shock, as when the shoe strikes a hard surface, and wherein the legs spring back to their original position after said shock. Specifically the shoe includes a pivoted section core member coated with a relatively thick layer of resilient material, and stop means are provided for limiting relative movement of the core sections while the resilient coating is of sufficient strength to urge the legs of the shoes toward a predetermined position.

A further object of the invention is a novel core member for an open sided pitching shoe or the like wherein two or more arms of metal or a similar heavy rigid material are joined at adjacent ends for limited relative movement. Specifically these arms are pivotally interconnected and formed with suitable stop shoulders at the pivotal joints.

Further objects of the invention will presently appear as the description proceeds in connection with the appended claims and the annexed drawing in which

Figure 1 is a plan view of an open sided pitching shoe of the invention.

Figure 2 is a plan view of the novel sectional core of the shoe of Figure 1.

Figure 3 is an end view of the core of Figure 2, and

Figure 4 is a section taken through line 4—4 in Figure 1 with the core covering broken away from one leg of the shoe.

Referring to Figure 1, the pitching shoe 11 comprising the preferred embodiment of the invention comprises a base portion 12 having a pair of outstanding legs 13 and 14 which extend generally parallel to each other so that the shoe is generally U-shaped and similar in appearance to the well known open sided horse shoe.

Legs 13 and 14 terminate in hook heels or projections 15 and 16 respectively which extend toward each other to partially restrict the opening between the ends of legs 13 and 14, and which further serve as hooks for engaging the pin or stake to aid in maintaining the shoe about the pin once it has been accurately thrown thereupon. In external appearance shoe 11 is similar to the pitching shoe illustrated in my Design Patent No. 92,642 issued July 3, 1934.

Shoe 11 comprises a flexible, sectional core member 17 inserted or imbedded in a relatively thick coating or covering 18. As illustrated in Figures 1 and 2, core 17 comprises a pair of rigid arms 19 and 21, preferably of generally rectangular cross section. Arms 19 and 21 are inserted or imbedded within and extend along legs 13 and 14 respectively; and are generally L-shaped, being curved toward each other at adjacent ends to extend through base 12 to a pivotal interconnecting joint designated at 22 in Figure 1 and preferably at about the middle of base 12 so that arms 19 and 21 are of equal length.

Referring to Figures 2 and 3, arms 19 and 21 are formed at their adjacent ends upon opposite sides with relatively thin ears 23 and 24 respectively which interfit with their inner surfaces 25 and 26 in full surface sliding engagement.

Arms 19 and 21 are pivotally secured together at joint 22 by a suitable rivet 27 which passes through ears 23 and 24 and is preferably rigid with arm 21 and upon which arm 19 is journaled. The dimensions of ears 23 and 24 and rivet 27 are so chosen that joint 22 will be about the same thickness as either arm 19 and 21 as illustrated in Figure 4.

Inwardly of surface 26, arm 21 is formed with a stop shoulder 28 designed to be engaged by or otherwise serve as a stop for opposite corners of ear 23 as the arms are relatively displaced about joint 22. Inwardly of surface 25, arm 19 is provided with a similar stop shoulder 29 for engaging or otherwise serving as a stop for the opposite edges of ear 24. Stop shoulders 28 and 29 thereby limit relative rotation of either arm 19 and 21 about pivot joint 22 in either direction to a predetermined amount as illustrated in dotted lines in Figure 2.

While core member 17 is illustrated as generally flat and made of only two sections, it may be made of any desired cross-section and in any desired number of interconnected sections without departing from the spirit of the invention. Moreover, joint 22 may be of any suitable type 45 permitting limited relative movement, pivoted, sliding or otherwise between the rigid arms of the articulated core member.

Preferably core member 17 is made of a metal, such as malleable iron or some other relatively 50 heavy rigid material.

Core member arms 19 and 21 terminate in projections 31 and 32 which extend toward each other and are adapted to extend within the hook heels 15 and 16 respectively when the core member is within covering 18. Core member 17 is relatively heavy and its weight is generally evenly distributed throughout the shoe so that perfect balance is obtained.

The coating or covering 18 may be any suitable 60 material having a relatively soft surface capable of resisting wear, and preferably is made of relatively soft vulcanite, or a suitable soft, tough rubber or rubber and fabric compound which is preferably permanently attached or secured about the core member by a suitable molding or vulcanizing operation. During the molding or vulcanizing process some of the rubber or other material may fill the space between stop shoulders 28 and 29 and the ears 23 and 24, but such material is compressible to permit relative rotation of the core arms about the pivoted joint and does not interfere with normal operation of the latter. It is preferable that covering 18 be made of a resilient material for purposes to be later 75 described.

Shoe 11 is also formed with an elongated calk 33 on base 12 and smaller calks 34 and 35 adjacent the ends of legs 13 and 14 respectively. These calks are preferably integral with covering 18 and serve to further balance the weight of the 5 shoe.

Due to its relatively soft resilient surface which has no sharp corners or rigid projections, shoe 11 is especially adaptable for use indoors and under similar circumstances. Core member 17 is of 10 such weight and is so disposed within the shoe that shoe 11 is a relatively heavy, balanced article which is favorably comparable with the steel shoes used for outdoor games. Covering 18 is especially selected for its resilience, durability and 15 resistance to cuts and shocks.

When shoe 11, after being thrown through the air, falls on one leg it remains substantially in the area where it lands and does not bounce excessively. This "dead" landing is due to the fact 20 that the leg gives, the core arm in that leg rotating about its pivotal joint, thereby absorbing most of the landing shock. This movement of the core arm is resiliently resisted by the resilient covering and is limited to a predetermined degree by 25 the stop shoulders on the core arms. A shoe having a rigid core and a resilient covering will bounce excessively.

By the time shoe 11 has come to rest after such a landing, it will have reassumed its original shape 30 as defined by the resilient covering 18 since the resiliency of that covering overcomes the temporary deformation of the shoe due to landing and pulls the bent leg and its enclosed core arm back to normal position. In shoes having rigid 35 one piece cores the core is progressively bent by such repeated landing shocks, and has to be straightened or bent back to shape periodically. This defect is entirely eliminated by the present 40 invention.

Thus the present invention provides a pitching shoe which is durable and has substantially the same balance and weight as an outdoor shoe, which falls with a dead landing and does not rebound or bounce excessively, and which maintains its shape even during constant use.

While the core member has been illustrated as entirely imbedded in the rubber covering, it will be understood that the invention embraces pitching shoes wherein a core is inserted, in a surface channel or slot along one surface of the shoe, and secured therein by a suitable adhesive or by vulcanization and any other arrangement wherein a portion or portions of the core may be accessible through an opening or openings in the covering.

The invention is also clearly applicable to round or circular pitching shoes such as quoits wherein an annular ring of rubber or the like is provided with a plurality of pivotally interconnected rigid metal core sections extending circumferentially 60 within the quoit.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the 70 claims are therefore intended to be embraced therein.

What is claimed and desired to be secured by United States Letters Patent is:

1. An open sided indoor pitching shoe of gen- 75

erally U or horseshoe-shape comprising a core member having a pair of rigid metal arms with integral curved extensions pivotally interconnected at adjacent ends and a relatively thick integral coating of rubber or an equivalent relatively soft, tough material permanently bonded upon said core.

5. 2. An indoor pitching shoe or the like of given configuration comprising a cover of relatively soft, tough, durable material for preventing injury to wooden floors, furniture and similar surrounding objects and a relatively heavy flexible core entirely and permanently embedded within said cover, the flexibility of said core permitting 10 deformation of the shoe upon landing after being thrown by a player and thereby cooperating with said material to take up the shock of said landing and prevent undesirable and excessive bounding of said shoe and said tough cover being resilient to the extent of effecting return of said 15 shoe to said configuration after said deformation.

3. An indoor pitching shoe of given configuration comprising a heavy flexible core of metal permanently and entirely embedded within a relatively thick covering of tough rubber or like material, said core being of such flexibility as to permit temporary deformation of said shoe to absorb landing and similar shocks to which the shoe is subjected when thrown by a player to 20 thereby prevent undesired bouncing and said shoe being sufficiently resilient to return to substantially original shape after said deformation.

4. An open sided indoor pitching shoe of generally horseshoe-shape having a base and a pair 25 of spaced legs, an integral cover of rubber or like tough, resilient material of substantial thickness

and a heavy flexible metal core extending through said base and both legs, said core being wholly embedded within said cover and permanently bonded thereto, and said core being of such flexibility as to permit temporary deformation of 5 said shoe to absorb landing and similar shocks to which the shoe is subjected when thrown by a player to thereby prevent undesired bouncing and said shoe being sufficiently resilient to return to substantially original shape after said deforma- 10 tion.

5. An open sided indoor pitching shoe comprising a generally U-shaped integral element of relatively soft, tough material and a heavy articulated metal core permanently and wholly 15 embedded within said element, said core being sufficiently flexible to permit temporary deformation of said shoe to absorb landing and similar shocks to which the shoe is subjected when thrown by a player to thereby prevent undesired 20 bouncing and said shoe being sufficiently resilient to return to substantially original shape after said deformation.

6. An open sided balanced indoor pitching shoe comprising a generally U-shaped element of resi- 25 lent material having a base and a pair of legs, and flexible core wholly embedded within said element and extending along substantially its whole length, said core comprising a pair of heavy rigid core sections extending from said legs into said 30 base where they are interfitted and pivotally interconnected.

7. In the pitching shoe defined in claim 6, a stop projection on one of said core sections for limiting relative rotation of said sections. 35
